UNITED STATES PATENT OFFICE.

CHARLES B. MEAD, OF EAST PALESTINE, OHIO.

RAIL-JOINT.

SPECIFICATION forming part of Letters Patent No. 699,966, dated May 13, 1902.

Application filed February 13, 1902. Serial No. 93,837. (No model.)

To all whom it may concern:

Be it known that I, CHARLES B. MEAD, a citizen of the United States of America, residing at East Palestine, in the county of Columbiana and State of Ohio, have invented 5 certain new and useful Improvements in Rail-Joints, of which the following is a specification, reference being had therein to the accompanying drawings.

This invention relates to certain new and useful improvements in rail-joints, and relates more particularly to that class known as "combined fish-plates and chairs."

The present invention has for its object 15 the provision of novel means whereby the rail-sections may be securely fastened together and the rails prevented from creeping; furthermore, provide a device that will be extremely simple in construction, strong, durable, comparatively inexpensive, and highly efficient in its use.

The invention further aims to provide a rail-joint that may be easily removed and replaced when desired; furthermore, to provide 25 means that will effectually relieve the nuts and bolts from the strain when the rails expand and contract.

A still further object of the present invention is to provide a rail-joint that will secure 30 the rails together in a manner that will take up the jar incident to heavy trains and will practically cushion the rails to a great extent and obviate and take up to a great degree the jar that is caused when the train is 35 passing from one rail-section to another.

With the above and other objects in view the invention consists in the novel combination and arrangement of parts to be hereininafter more fully described, and specifically 40 pointed out in the claim.

In describing the invention in detail reference is had to the accompanying drawings, forming a part of this specification, and wherein like numerals of reference indicate like 45 parts throughout the several views, in which—

Figure 1 is a perspective view of my improved rail-joint, showing the same applied in proper position to the rails. Fig. 2 is an end view thereof. Fig. 3 is a vertical sectional view of the same. Fig. 4 is a rear elevation of one of the fish-plates. Fig. 5 is a top plan view of the rail with the web thereof

in longitudinal section. Fig. 6 is a detail end view of one of the fish-plates, forming a part of the chair.

In the drawings the reference-numeral 1 indicates the rails, having notches 2 formed therein, and 3 represents the cross-ties. The fish-plates 4 have openings 5 formed therein to receive the bolts which extend through the 60 web of the rail, said fish-plates carrying a base 6, the sections of which fish-plate carrying this base 6 form the chair for the rail. At the junction of the integral fish-plates and base are secured stops 7, which also are formed 65 integral with the fish-plate. These stops are suitably spaced apart and are adapted to register in the openings 2 formed in the base of the rail. These openings 2 and stops 7 formed on the opposite side of the rails are 70 not opposite one another, but are staggered for the purpose of strengthening the rails at their meeting ends. A clamp 8 is secured to the chair portion of the base and extends under the same, said clamp serving to securely 75 bind and retain the fish-plate and chair portions in proper position. Spikes 9 serve to fasten the rail-joint to the cross-ties 3. These spikes may be secured in openings formed in the side to the base portion 6 and are driven 80 into the cross-ties 3. Bolts 10 pass through the fish-plates through the web of the rail and are adapted to receive the nuts 11, although I have shown only two nuts and two bolts, yet any number may be used, if desired. 85

It will be noted that the clamp for securing the fish-plate in position may be dispensed with, if so desired.

The many advantages obtained by the use of my improved device will be readily apparent from the foregoing description taken in connection with the accompanying drawings.

It will be noted that various changes may be made in the details of construction without departing from the general spirit of my 95 invention.

Having fully described my invention, what I claim as new, and desire to secure by Letters Patent, is—

In a rail-joint, the combination with the 100 rails having openings formed in the sides of the base thereof in staggered relation to each other, of a chair comprising two sections each having base portions and carrying integral

fish-plates extending to the under side of the rail - head, stops secured between the fish-plates and the base portions adapted to be received within said openings in the rail-base sides, an integral clamp extending under the bases of the chair and having its ends bent to engage the upper portion of the chair, spikes engaging in the ties for limiting the movement of the chair, and a series of nuts and

bolts extending through the fish-plates and to the webs of the rails, substantially as described.

In testimony whereof I affix my signature in the presence of two witnesses.

CHARLES B. MEAD.
